UNITED STATES PATENT OFFICE.

JOHN WELLINGTON RICHARDSON, OF EAGLE CORNERS, WISCONSIN.

RAILWAY CROSS-TIE.

1,001,165.

Specification of Letters Patent. Patented Aug. 22, 1911.

Application filed June 3, 1911. Serial No. 631,078.

To all whom it may concern:

Be it known that I, JOHN WELLINGTON RICHARDSON, a citizen of the United States, residing at Eagle Corners, in the county of Richland and State of Wisconsin, have invented certain new and useful Improvements in Railway Cross-Ties, of which the following is a specification, reference being had to the accompanying drawings.

10 This invention relates to new and useful improvements in railway cross-ties of the type composed of metal to serve as a substitute for the usual wooden tie, and has for its object to provide an improved tie of 15 this character, which may be readily and cheaply constructed preferably of rolled metal which possesses the requisite strength and cheapness, and which is provided with means which in practice serve to effectually 20 lock the rails thereto.

Another object of my invention is to provide a tie of this character which will possess advantages in points of efficiency, durability, is inexpensive of manufacture and at 25 the same time being simple in construction and operation.

With the foregoing and other objects in view, the invention consists in the novel features of construction and the combination 30 and arrangement of parts hereinafter more fully described, pointed out in the claims and shown in the accompanying drawings in which,

Figure 1 is a perspective view of a tie 35 constructed in accordance with my invention. Fig. 2 is a longitudinal sectional view, and Fig. 3 is a transverse sectional view.

Referring more particularly to the drawings, 1 indicates the base comprising a 40 single piece of metal of the desired length and width, and having its longitudinal edges bent upon themselves, as shown at 2.

The tie plate 3 is formed of a single piece 45 of metal and is substantially of inverted U-shape form and provided with the flanges 4 on each side thereof, having the longitudinal edges 2 of the base plate engaged there-over forming a substantial tie.

The tie plate 3 is to be reinforced by the 50 braces 5, each of which is composed of a single strip of metal bent into substantial U-shape form, having the side 6 somewhat wider than the other, these U-shape braces

being turned on edge and inserted under the tie plate so that the large side 6 rests on 55 the base 1 and the small side bears against the top, the braces, when inserted, being placed so that they are oppositely disposed, as shown in Fig. 3. These braces are held rigidly in place by the bolts 7.

The rails 8 are secured to the tie by means of a rail plate 9 secured to the tie-plate and having its ends 10 bent upon themselves to engage over the outside flange of the rail. A retaining plate 11 is employed, having its 65 ends 12 reinforced by bending them upon themselves and then disposed over the inner flange of the rail, the plate being then rigidly secured to the tie by means of the bolts 13 passing through the plate and disposed adjacent the edge of the inner flange of the rail. At curves and switches where a good deal of strain falls on the rail the braces 14 are provided and are secured at 70 one end to the tie by means of the bolts 15. The other ends of the braces are turned upwardly and adapted to be disposed up against the web of the rail and under the head as clearly shown in Fig. 2.

From the foregoing description, it will be 80 plainly seen that a tie constructed in accordance with my invention, will possess durability and strength and can be manufactured at a very low cost.

While I have shown and described the 85 preferred construction of my invention, it will be obvious that various changes in the details of construction and in the proportions may be resorted to for successfully carrying my invention into practice without 90 sacrificing any of the novel features or departing from the scope thereof.

What I claim is:—

1. In a railway cross-tie, comprising a base, a hollow metallic body secured thereto, U-shaped braces turned on edge and inserted within said body and oppositely disposed therein, and means for securing the rails to the top of said body.

2. In a railway cross-tie, comprising a 100 base, an inverted U-shaped tie plate, flanges formed on the lower edges of said tie plate, having the longitudinal edges of the base bent upon themselves and engaged there-over, braces disposed beneath the tie plate 105 and rigidly secured thereto, and means se-

cured to the top of said plate for fastening the rails thereto.

3. In a railway cross-tie, comprising a base, an inverted U-shaped tie plate secured thereto, U-shaped braces having one side somewhat wider than the other and oppositely disposed within the tie plate so that the wide side rests on the base and the small

side bears against the top, and means for securing the rails to the tie plate.

In testimony whereof I hereunto affix my signature in the presence of two witnesses.

JOHN WELLINGTON RICHARDSON.
